UNITED STATES PATENT OFFICE.

GEORGE H. HAYES, OF HAZELTON, KANSAS.

FUEL-HEATER FOR EXPLOSIVE-ENGINES.

1,307,124.

Specification of Letters Patent. Patented June 17, 1919.

Application filed August 13, 1917. Serial No. 186,068.

To all whom it may concern:

Be it known that I, GEORGE H. HAYES, a citizen of the United States, residing at Hazelton, in the county of Barber and State 5 of Kansas, have invented a certain new and useful Improvement in Fuel-Heaters for Explosive-Engines, of which the following is a specification.

My invention relates to improvements in 10 fuel heaters for explosive engines.

The object of my invention is to provide novel means for supplying heated fuel to an explosive engine, so that the engine may be easily and quickly started in cold weather.

15 The novel features of my invention are hereinafter fully described and claimed.

In the accompanying drawing which illustrates the preferred embodiment of my invention,

20 Figure 1 is an elevation, partly broken away, of an ordinary carbureter and manifold provided with my improvement.

Fig. 2 is an enlarged vertical sectional view of the fuel container of the heater, a 25 portion of the fuel conductor heated thereby being shown in elevation.

Fig. 3 is a top view of what is shown in Fig. 2.

Similar reference characters designate 30 similar parts in the different views.

1 designates an ordinary carbureter which discharges into the intake end of a common manifold such as is employed on explosive engines.

35 3 designates a liquid fuel conductor having a branch 4 leading to the carbureter and provided with a branch 5 which discharges into the intake portion of the manifold 2.

In the branch 5 is provided a shut-off 40 valve 6.

For heating the liquid fuel before it enters the carbureter, independently of the engine with which the carbureter may be connected, the branch 5 is provided with a 45 coiled portion 7, preferably located below the manifold 2 and disposed in a fuel container, preferably comprising a cup 8, which is supported by a clip 9 which embraces the branch 5.

50 The upper portion of the side walls of the container 8 may be provided with perforations 10 for admitting air to support com-

bustion of the fuel held within the container.

In the operation of my invention, fuel, 55 such as gasoline, is poured into the container 8 and lighted, after which the shut-off valve 6 is opened, thus permitting fuel to pass through the branch 5 into the manifold 2. The burning fuel in the container 60 8 heats the coiled portion 7 and the manifold 2, thereby heating the fuel, such as gasoline, which passes through the branch 5 into the manifold. The engine may be readily started with the heated fuel, following 65 which the shut-off valve 6 is closed, and the manifold is thereafter supplied with the explosive mixture which is discharged from the carbureter 1 into the manifold 2.

I do not limit my invention to the structure shown and described, as modifications, within the scope of the appended claims, may be made without departing from the spirit of my invention.

What I claim is:

75 1. A carbureter, a manifold connected therewith, a liquid fuel conductor having two branches respectively discharging into the carbureter and into the manifold, a shut-off valve in the branch leading to the manifold, and means independent of an engine 80 to which the carbureter may be connected for heating the branch which leads to the manifold.

2. A carbureter, a manifold connected 85 therewith, a liquid fuel conductor having two branches respectively discharging into the carbureter and into the manifold, a shut-off valve in the branch connected with the manifold, and a fuel container located 90 so that heat from burning fuel contained therein will heat the branch leading to the manifold.

3. A carbureter, a manifold connected 95 therewith, a liquid fuel conductor having two branches respectively discharging into the carbureter and into the manifold, a shut-off valve in the branch connected with the manifold, the branch connected with the manifold having a coiled portion, and a container for liquid fuel in which said coiled portion is located.

100 4. A carbureter, a manifold connected therewith, a container adapted to hold burn-

ing fuel, and a liquid fuel conductor dis- with a shut-off valve and having a coiled charging into the manifold and having a portion, and a container for liquid fuel hav- 10 coiled portion located in said container: ing an open top and encircling said coiled

5. A carbureter, a manifold connected portion. therewith, a liquid fuel conductor having two In testimony whereof I have signed my branches respectively discharging into the name to this specification. carbureter and into the manifold; the branch carbureter connected with the manifold being provided

GEORGE H. HAYES.
